UNITED STATES PATENT OFFICE.

WILLIAM F. KIESEL, JR., OF ALTOONA, PENNSYLVANIA.

ARRANGEMENT OF WATER-GAGE COCKS.

1,388,115.

Specification of Letters Patent. Patented Aug. 16, 1921.

Application filed October 29, 1918. Serial No. 260,160.

To all whom it may concern:

Be it known that I, WILLIAM F. KIESEL, Jr., a citizen of the United States, and residing at Altoona, Blair county, State of Pennsylvania, have invented certain new and useful Improvements in the Arrangement of Water-Gage Cocks, of which the following is a specification.

My invention has for its purpose to determine the height of water in a boiler and especially in that class of boilers which are movable or portable, as locomotive boilers, and in which the tilting or change of horizontal inclination of the boiler makes it difficult to determine the actual level by a series of gage cocks arranged and communicating with the boiler in the usual manner. To this end I combine with a series of gage cocks a series of pipes terminating within the boiler at different heights, and at that point in the boiler where the water is least liable to change of level from the tilting of the boiler, so that the engineer cannot be misled on testing the cocks by the changes in the position of the water resulting from alterations in the position of the boiler. My invention also embodies certain details of construction as fully described hereinafter and as illustrated in the accompanying drawing in which:—

Figure 1 is a longitudinal part section of sufficient of a locomotive boiler to illustrate my improvement;

Fig. 2 is a plan view;

Fig. 3 is an end view taken from the rear;

Fig. 4 is an enlarged rear view of the combination gage cock casing;

Fig. 5 is a side view of the construction shown in Fig. 4; and

Fig. 6 is a section on the line 6—6 of Fig. 4.

My invention may be used in connection with different types of boilers and the drawings illustrate part of a boiler A, such as a locomotive boiler, having a fire-box at the rear end. Within the boiler I arrange a series of pipes 2, 2 extending through the rear head of the boiler and provided outside the boiler each with a gage cock D, the inner ends of the pipes supported by a suitable bracket E at different heights above the crown sheet. In the class of boilers shown the inlet ends of the pipes may be bent down as shown and located near the rear flue sheet, thus being over the highest point of the crown sheet. In any case, however, the inlet ends

of the pipes are at or adjacent to that section of the boiler where the level of the water is least affected by any change in the inclination or tilting of the boiler. As a result the actual level of the water, as indicated by testing the cocks, may be ascertained, and the engineer will not be misled, as is the case when the cocks communicate with the boiler only at the rear end, by those changes in the height of the water in respect to the crown sheet, which occur from changes in the position of the boiler.

The gage cocks may be connected to communicate with and discharge the water from the different pipes 2, in different ways, but I have shown a unitary or combination gage cock casing B consisting of a continuous block provided with a flange 4 adapted to be bolted to the end of the boiler and having a series of independent chambers α , each socketed to receive the end of one of the pipes 2, and each communicating with a hollow neck 5 socketed to receive the threaded end or nipple of a gage cock D.

As shown, each chamber α is threaded internally and is open at the forward end, the opening surrounded by a tapered seat y adapted to receive the flaring end or flange z of one of the pipes 2, and a hollow plug C threaded to screw into the chamber α is provided with a boss 7 which, when the plug is screwed in, is brought to bear firmly against the interior of the flanged end of the pipe pressing the latter against its seat and making a tight joint. A screw plug 8 serves as a means of closing the outer end of each chamber α .

The casing B is provided with a central recess s , in its front face and all of the chambers α open out of this recess. The pipes 2 may be positioned by inserting them through the chambers α , and thereafter screwing up the plugs C and 8. Each pipe may be withdrawn by first removing the plugs 8 and C.

By thus providing a single block or casing adapted for the connection of all of the pipes and all of the cocks, the attachment of the indicator appliance to a boiler is quickly, easily and economically effected, and possible leakage is reduced to a minimum.

Preferably, the vertical arrangement of gage cocks follows that of the front terminals of the pipes 2, that is, the lower pipe connects with the lower gage cock and the

others in order, so that the relative position of the gage cocks indicates to the engineer the relative positions of the pipe terminals. Further, the open or inlet ends of the pipes 5 2 are disposed so that they are spaced and located to correspond to the usual gage cocks. Thus the arrangement herein described provides means for determining the water level at a point adjacent the high end 10 of the crown sheet.

Without limiting myself to the precise construction and arrangement of parts shown, I claim:—

1. The combination with a series of pipes 15 extending from the end of a boiler toward the center thereof and terminating at different levels within the boiler, of a single casing having independent chambers with sockets for the rear ends of said pipes, and 20 gage cocks connected with the casing and communicating independently with the different chambers, substantially as described.
2. A gage cock casing provided with a series of chambers with sockets adapted to 25 receive the ends of a series of pipes extending into a boiler, a hollow neck communicating with each chamber, and gage cocks connected one with each of the necks, substantially as described.
3. A combination gage cock casing consisting of a single block having independent chambers and sockets to receive the ends 30 of pipes extending into the boiler, and a hol-

low neck communicating with each chamber and with a socket to receive the nipple of 35 a gage cock, substantially as described.

4. A combination gage cock casing consisting of a single block with a flange for bolting to a boiler, having independent chambers and sockets to receive the ends of pipes 40 extending into the boiler, and a hollow neck communicating with each chamber and with a socket to receive the nipple of a gage cock, substantially as described.

5. A combination gage cock casing having 45 a series of independent threaded chambers, each with an internal tapering seat and an opening to receive the end of a pipe with a flaring flange adapted to said seat, and a hollow screw plug fitting said chamber and 50 with a boss adapted to the interior of the flanged end of said pipe, substantially as described.

6. A combination gage cock casing having 55 a series of independent threaded chambers, each with an internal tapering seat, and an opening to receive the end of a pipe with a flaring flange adapted to said seat, and a hollow screw plug fitting said chamber and 60 with a boss adapted to the interior of the flanged end of said pipe, and a screw plug closing said chamber at the outer end, substantially as described.

In testimony whereof I affix my signature.

WILLIAM F. KIESEL, JR.
